UNITED STATES PATENT OFFICE.

RAYMOND BAKER, OF PHILADELPHIA, PENNSYLVANIA.

CIGAR-TIP-CUTTING ATTACHMENT AND FASTENING DEVICE FOR CIGAR-BOXES.

No. 895,835.

Specification of Letters Patent.

Patented Aug. 11, 1908.

Application filed January 11, 1908. Serial No. 410,385.

To all whom it may concern:

Be it known that I, RAYMOND BAKER, a citizen of the United States, residing at Philadelphia, in the county of Philadelphia and State of Pennsylvania, have invented a certain new and useful Improvement in Cigar-Tip-Cutting Attachments and Fastening Devices for Cigar-Boxes, of which the following is a specification.

10 My invention relates to a new and useful improvement in cigar tip cutting attachment and fastening device for cigar boxes, and has for its object to provide an exceedingly simple and effective device by means of which 15 the tips of cigars may be readily cut off and collected within the cigar box, and another object is to so construct a tip cutting device as to provide a fastening which will keep the lid of the box closed.

20 With these ends in view, this invention consists in the details of construction and combination of elements hereinafter set forth and then specifically designated by the claims.

25 In order that those skilled in the art to which this invention appertains may understand how to make and use the same, I will describe its construction in detail, referring by letter to the accompanying drawing forming a part of this specification, in which—

Figure 1 is a vertical transverse section of a cigar box having my improved tip cutter attached thereto, a piece of a cigar and the tip therefrom and the lid of the box closed 35 shown in dotted lines. Fig. 2, is a vertical section thereof at the line $x-x$ of Fig. 1, looking in the direction of the arrow. Fig. 3, is a front elevation of a cigar box partly broken away to show the conical hole into 40 which the cigar is inserted. Fig. 4, is a perspective view of the cutter, Fig. 5, is a perspective view of the perforated cutting plate, and Fig. 6, an elevation of a modified form of cutter.

45 In carrying out my invention as here embodied, A represents the body of the cigar box and B the lid thereof. The front wall of the cigar box is provided with a conical hole C cut so as to form a recess beneath the 50 lid, as indicated at C'.

Back of the hole C is attached to the wall a perforated plate D by means of the fastening

points D³, the upper edge of which is turned over, as indicated at D' so as to extend over the top of the inner front wall of the cigar 55 box, thus forming a support for the conical hole C and a guide for the cutter E, which is rigidly secured to the lid of the cigar box by means of the fastening points E'. On this cutter is also formed the projection E², so 60 that when the lid is closed this projection will snap into the conical hole D² formed in the cutting plate D, thus holding the lid of the box in a closed position.

In Fig. 6 I have shown a slightly modified 65 form of cutting plate in so much as the cutting edge is formed by cutting a V-shaped notch therein, and it will be readily seen that when this cutting plate comes in contact with the cigar, two cutting edges will be 70 brought to bear on the same and readily cut the tip therefrom. This cutting plate would also have the projection F' formed thereon so that when the lid of a cigar box is closed it will engage with the conical hole formed in 75 the cutting plate thus holding the lid of the box in a closed position.

In practice, when a person wishes to take a cigar from the box he places his finger in the recess formed by the hole C beneath the 80 lid and is thus enabled to apply a great amount of power upon the lid, and it also relieves him of having to use his finger nails or a knife. When the cigar is removed from the box and it is desired to cut the tip therefrom, the cigar is placed in the conical hole C and passes through the hole D², then the lid is closed down, which action cuts the tip 85 from the cigar and allows the projection E² to engage with the hole D², thus fastening 90 the lid and collecting the tip within the box.

Having thus fully described my invention, what I claim as new and useful, is—

1. In combination with a cigar box provided with a lid, coöperating means carried 95 by the box and lid whereby when said lid is closed a cigar may be cut and said lid automatically locked to said box at the completion of the cutting operation.

2. In combination with a cigar box provided with a lid, means for cutting the tip from a cigar and in the same continuous operation locking said lid in closed position embodying a perforated plate secured to said

box, and a cutting member to coöperate with said plate to cut the cigar tip, said cutting member being provided with a projection located to the rear of its cutting edge and 5 adapted to enter said perforation of the first named plate immediately following the cutting operation.

In testimony whereof, I have hereunto affixed my signature in the presence of two subscribing witnesses.

RAYMOND BAKER.
